UNITED STATES PATENT OFFICE.

PETER S. LARSON, OF BELOIT, WISCONSIN.

CLOCKWORK.

1,408,366.

Specification of Letters Patent. Patented Feb. 28, 1922.

Application filed May 28, 1921. Serial No. 473,228.

To all whom it may concern:

Be it known that I, PETER S. LARSON, a citizen of the United States, residing at Beloit, in the county of Rock and State of Wisconsin, have invented certain new and useful Improvements in Clockworks; and I do declare the following to be a full, clear, and exact description of the invention, such as will enable others skilled in the art to 10 which it appertains to make and use the same.

This invention relates to an improved construction in clockworks and one object of the invention is to provide a clock having a spring driving mechanism for the time gearing and spring driving mechanism for the alarm gearing which will be interchangeable with the spring driving mechanism for the time gearing thus permitting the driving 15 mechanism for the alarm mechanism to be substituted for the driving mechanism of the time gearing in case the driving mechanism for the time gearing should become broken or out of order.

Another object of the invention is to so construct this clockwork that each of the spring driving mechanisms may be bodily removable through an enlarged opening in the rear plate of the gear carrying frame.

Another object of the invention is to so construct the spring driving mechanism that the spring thereof will be enclosed in a spring cup loosely mounted upon a main shaft which further carries a main gear having a disk rigid therewith and forming a closure for the open end of the spring cup, the disk and cup being interlocked so that the cup which will be rotated from the spring may transmit rotary movement to 30 the large or main gear through the medium of the disk closing the open end of the cup.

Another object of the invention is to so construct the clockwork that the hammer carrying rocker shaft of the alarm mechanism may have one end journalled in the forward plate of the gear frame and the second end portion journalled in a bearing carried by a bearing strip rotatably mounting the main shaft of the spring power 45 mechanism of the alarm, thus permitting the hammer carrying shaft to be easily removed when desired, by simply releasing the bearing strip.

Another object of the invention is to provide a mechanism of the type set forth which will be very compact in construction.

Another object of the invention is to so construct the driving mechanism or power mechanism that the main shaft thereof may be rotated when winding in the same direction that the cup moves when the clock is in operation.

Another object of the invention is to provide improved pawl and ratchet means for holding the springs wound.

This invention is illustrated in the accompanying drawings, wherein:

Figure 1 is a view showing the rear closure plate of the clock casing removed and the clockworks in rear elevation.

Figure 2 is a view showing the casing in section and the clockworks in side elevation.

Figure 3 is a vertical sectional view taken along the line 3-3 of Fig. 2 with parts omitted.

Figure 4 is a sectional view taken along the line 4-4 of Fig. 1.

Figure 5 is a perspective showing the mounting for the rear end of the hammer carrying rocker shaft of the alarm mechanism.

This improved clock structure includes a casing 1 which is provided with a rear wall 2 or closure plate which is removably held in place so that it can be removed when desired. The clockworks are mounted in this casing 1 and will be provided with the usual dial 3 and frame for carrying the gearing. The gearing for the most part is of a conventional construction and is mounted between the two plates 4 and 5, the plate 4 being the forward plate and the plate 5 the rear plate. This rear plate 5 is provided with enlarged openings 6 and 7 through which the spring driving or power mechanism may be removed as will be herein-after brought out. Bearing strips 8 are secured to the rear plate 5 for removal therefrom and these strips 8 extend across the openings 6 and 7 as shown in Fig. 1. It 100 should be noted that one of these plates is provided with an offset 9 at one end in which will be provided a bearing 10 to receive the end of the rocker shaft 11 which carries the hammer 12. The plate 5 is broken away at 105 this point so that the rocker shaft can be readily removed when the strip 8 of the alarm gearing is removed.

Since the spring power or driving mechanism for the time gearing is identical with that for the alarm gearing, a description of one will suffice for both and therefore it will

be understood that the following description applies to both of the spring driving mechanisms. This driving mechanism includes a shaft 13 which is enlarged intermediate its length as shown at 14 to provide abutment shoulders at the ends of the enlargements. One end portion of the shaft is threaded as shown at 15 and a squared portion 16 is provided so that a ratchet 17 may be held 10 against rotating upon the shaft. A spring cup 18 is loosely mounted upon this shaft 13 and is provided with a hub portion which fits closely upon the shaft between the enlargement 14 and the bearing strip 8 which 15 fits upon the shaft and engages the hub portion of the cup. After the strip 8 has been placed upon the shaft, the ratchet wheel 17 is put in place and a securing nut 19 is then screwed upon the shaft to engage the ratchet 20 wheel and hold the ratchet wheel upon the squared portion of the shaft. A spring 20 is placed within the cup 18 about the shaft and has its inner convolution connected with the shaft and its outer convolution connected 25 with the cup as shown in Fig. 4. It will thus be seen that when the shaft is rotated, the spring may be wound. In order to hold the spring wound, there has been provided a pawl 21 which is pivotally connected with the strip 8 and has its free end portion which engages the ratchet provided with an opening through which will extend the spring 22 for holding the pawl in engagement with the ratchet. By having the spring 30 pass through an opening formed in the pawl, there is no danger of the spring slipping out of engagement with the pawl. It should be further noted that the pawl and ratchet are mounted to the rear of the spring 8 where 35 they may be easily reached when necessary. The large gear 23 is provided with a hub 24 which fits upon the shaft 13 between the enlargements 14 and the forward plate 4 and carries a disk 25 which fits into the 40 cup 18 to close the open end thereof. This disk 25 is provided with side lugs 26 which fit into notches 27 formed in the cup and thus provide interlocking engagement between the disk and cup so that the disk will 45 turn the cup and thus rotary motion be 50 transmitted to the hub and gear 23 from the cup.

When assembling, the cup will first be placed upon the shaft and the spring connected with the cup and shaft. The strip 55 8 will then be put in place upon the shaft and after this strip is in place the ratchet wheel will be placed upon the shaft and secured by means of the nut 19 so that it 60 cannot move off of the squared portion of the shaft. The shaft and cup will then be passed through the openings of the plate 5 and the shaft passed through the hub 24 of the gear 23 and the lugs 26 positioned in 65 the notches 27 of the cup. The bearing

strip will then be secured upon the plate 5. After each of the driving mechanisms has been assembled as brought out, the clock-works will be placed in the casing 1 and the rear wall 2 will be put in place with the 70 securing rods 28 passing through openings in this rear wall. It is of course understood that the clockworks can be connected with the rear wall before the rear wall is connected with the casing if so desired. When 75 the clockworks are connected with the rear wall, the gong 29 will be positioned between the securing rods or bolts 28 and the hammer 12 will be positioned within the gong and will strike the gong when in operation. 80 The winding keys will be put in place upon the shafts 13 and will be turned toward the right in Fig. 1 to rotate the shafts and wind the springs. After the spring has been wound, the springs will have a tendency to 85 cause the cups to also turn to the right and as these cups turn, rotary movement will be transmitted to the gears 23 to operate the time gearing and alarm gearing. If the spring of the driving or power mechanism 90 for the time gearing should break, the securing nuts for the strips 8 can be removed, after the back has been released from the rods 28 and the strips will carry with them the cups and springs and also the two shafts 95 when removed. The gear 23 of the alarm gearing can be put away temporarily and the strip, cup, spring and shaft of the alarm gearing substituted for those of the time gearing until a new spring for the time gear- 100 ing can be obtained. When this strip for the alarm gearing is removed the rocker shaft 11 will be released and can be removed and put away with the gear 23. It will thus be seen that the power or driving mechanism 105 of the alarm gearing can be substituted for the power mechanism of the time gearing thus saving a great deal of inconvenience since the clock can still operate while a new power unit is being obtained or necessary re- 110 pairs made.

I claim:

1. A clockwork comprising a frame including a plate provided with an enlarged opening, gearing in said frame, and a power mechanism for said gearing, the power mechanism being removable in a body through the opening of said plate and including a shaft and a bearing for the shaft removably connected with the plate and extending across the opening. 115

2. A clockwork comprising a frame including a plate provided with enlarged openings, time gearing in said frame, alarm gearing in said frame, and interchangeable power mechanism for the time and alarm gearing, the power mechanisms being each removable in a body through one of said openings and each of said mechanisms including a shaft and a bearing strip for the 120 125 130

shaft removably carried by the plate and extending across the opening.

3. A clockworks comprising a frame including a forward plate and a rear plate 5 having enlarged openings formed therein, removable bearing strips extending across said openings, time gearing and alarm gearing between said plates and each including as its driving power a rotatable shaft journaled in the forward plate and one of said strips, a gear loose upon said shaft, a spring cup loose upon said shaft, a disk carried by said gear and closing said cup and releasably engaging said cup for turning with the cup, a spring in the cup connected with the cup and shaft, a ratchet carried by the shaft and a pawl carried by the strip for engaging said ratchet, the shaft, spring and cup being removable with the strip, and the 15 strip, cup and spring of the alarm gearing being interchangeable with the strip, cup and spring of the time gearing.

4. A clockworks including a frame, gearing mounted therein and including a rotatable spring shaft, a driving gear loose upon said shaft, a cup loose upon said shaft, a coiled spring in the cup having connection with the shaft and cup, a closure disk for the cup rigid with said gear and having interlocking engagement with the cup, a bearing carried by said frame and provided with an opening receiving said shaft, the bearing engaging the cup to hold the cup in interlocking engagement with said disk, a 30 ratchet carried by said shaft, and a pawl carried by said strip and engaging said ratchet.

5. A clockworks comprising a frame having a forward plate and a rear plate provided with an enlarged opening, a bearing 40 removably carried by said rear plate and extending across the opening, gearing between said plates including a shaft rotatably carried by the bearing and forward plate 45 and removable with said bearing, a spring cup loose upon said shaft and open at one end, a gear wheel loose upon the shaft, a

drive spring in the cup having connection with the cup and shaft, a closure disk for the open end of the cup rigid with the gear 50 and having interlocking engagement with the cup, a ratchet carried by said shaft and a pawl carried by said bearing and engaging said ratchet.

6. The combination with the structure of 55 claim 5, of alarm mechanism including a hammer carrying rocker shaft positioned between the plates and having one end journaled in the forward plate and its second end journalled in said bearing for permitting removal of the rocker shaft when the bearing is removed.

7. A clockworks including a frame having a forward plate and a rear plate provided with an enlarged opening, a bearing 60 strip removably carried by the rear plate and extending across the opening, gearing between said plates including a main shaft journalled in the forward plate and strip and extending rearwardly of the strip, a 70 spring cup loose upon said shaft and open at one end, a main gear loose upon said shaft, a spring in the cup coiled about said shaft and connected with the cup and shaft, a disk rigid with said gear and fitting into the open end of said cup and provided with side tongues fitting into notches of the cup to interlock the cup and gear for turning together, a ratchet carried by said shaft against the outer face of said strip and a 75 pawl carried by said strip and engaging said ratchet, the shaft and cup being removable through the opening of the rear plate when the strip is released.

8. The structure of claim 7 having the 80 shaft enlarged between the cup and disk to provide abutment shoulders limiting movement of the cup and gear toward each other, the outer portion of the shaft being reduced to provide an abutment shoulder engaged by 90 the ratchet.

In testimony whereof I have hereunto set my hand.

PETER S. LARSON.
